CLAIM

The ornamental design for a ski boot insert member, as shown and described.

DESCRIPTION

FIG. 1 is a top perspective view of a ski boot insert member showing my new design, this being for a left-foot boot;

FIG. 2 is a top plan view thereof;

FIG. 3 is a right side elevational view thereof;

FIG. 4 is a front elevational view thereof, looking from the toe towards the heel;

FIG. 5 is a rear elevational view thereof, looking from the heel towards the toe;

FIG. 6 is a left side elevational view thereof; and,

FIG. 7 is a bottom plan view thereof.

FIG. 1

FIG. 2

FIG. 3

FIG. 4

FIG. 5

FIG. 6
